UNITED STATES PATENT OFFICE.

HIRAM W. WHITE, OF ANDERSON, INDIANA.

IMPROVEMENT IN GUITAR-HEADS.

Specification forming part of Letters Patent No. **155,352**, dated September 22, 1874; application filed May 1, 1874.

To all whom it may concern:

Be it known that I, HIRAM W. WHITE, of Anderson, in the county of Madison and State of Indiana, have invented an Improvement in Guitars and other stringed instruments, of which the following is a specification:

My invention relates to an improved means for adjusting the strings on the tuning apparatus of a stringed instrument. My device consists in a hollow spindle turned by a rod fitted to slide within it. To this rod is attached the ordinary worm-wheel, having a knob with which to pull the said worm-wheel out of mesh or gear with the screw-key.

Any one who has played on the guitar, or other stringed instrument provided with screw-keys for fine adjustment, knows the amount of time that is occupied in taking up the slack in placing a string on the tuning apparatus. My device overcomes this difficulty, as I adjust the spindle directly, (instead of indirectly, as has been the custom heretofore,) and as rapidly as required.

Figure 1 is a horizontal view, partly in section, of my improved key-plate. Fig. 2 is a side view on the line 2 2, Fig. 1, partly in section. Fig. 3 is an inside view on the line 3 3, Fig. 1.

A represents an ordinary head-plate, on which the apparatus employed for adjusting the strings of a guitar or other instrument of like make is arranged. B represents a milled knob or head, attached to the worm-wheel b by any suitable means, being employed to draw the same out of mesh with the screw-key C. D represents a hollow spindle on which the string is wound, having perforations d d' for the reception of the ends of the string preparatory to winding. This hollow spindle D is grooved at end, and is inserted in a bearing, a, of the plate A. E represents a sliding rod attached with the worm-

wheel b to the knob B. This rod E is cut away at e to allow it limited play longitudinally of the spindle past the pintle p. This pintle p is inserted transversely of the hollow spindle D, and across the face of the cut e of the rod E, and prevents the latter from turning in the former. e' is a boss which prevents the rod E from being drawn out past the pintle p, and is formed by the cut e.

In use, one end of the string having been securely fastened by any suitable means to the heel-piece of the instrument, the other end is passed through the perforation d into the hollow spindle D and out through the other perforation, d'. The knob B is then pulled, drawing the worm-wheel b out of mesh and the boss e' against the portion of the string within the spindle, thereby clamping the string between the boss and pintle p. The spindle is then rotated by the knob B until the slack of the string is taken up. The rotating mechanism is then pushed back, thus bringing the worm-wheel b into mesh again with the screw-key C. The screw-key C is next turned until the string is brought into tune. For releasing the string the knob B is drawn out and rotated in opposite direction until the string is unwound, when, the rod being pushed back a little, the end of the string will be released.

The invention is applicable to guitars, violins, violoncellos, bass-violins, and other stringed instruments of analogous construction.

The following is claimed as new:

The hollow spindle D, sliding rod E, knob B, and worm-wheel b, in combination with the screw-key C, substantially as and for the purposes set forth.

HIRAM W. WHITE.
